UNITED STATES PATENT OFFICE.

HENRY HORSEFIELD, OF PHILADELPHIA, PENNSYLVANIA, ASSIGNOR TO
WILLIAM O. ROWLAND AND ALBERT E. SCHMIDT, OF SAME PLACE.

DESIGN FOR A LACE CURTAIN.

SPECIFICATION forming part of Design No. 25,376, dated April 14, 1896.

Application filed August 14, 1894. Serial No. 520,310. Term of patent 3½ years.

To all whom it may concern:

Be it known that I, HENRY HORSEFIELD, a subject of the Queen of Great Britain, residing in the city and county of Philadelphia, in the State of Pennsylvania, have invented and produced a new and original Design for Lace Curtains, of which the following is a specification, reference being had to the accompanying drawing, which shows a lace curtain illustrating my design.

In the accompanying drawing my design is shown centrally broken away.

The design for the lower piece P consists of the several figures *p*, combined with the flower-pieces *p'*, arranged between figures *p*. The upper piece R consists also of several figures *r* of the same general character as the figures *p*, though, as shown, they are of a slightly-different design, combined with flower-figures

of a somewhat similar character to those which form part of the figures *p'*, the general effect of the upper piece R being lighter than that of the lower piece P. The body Q of the net is ornamented with the light sprays *q* and figures *p''*, and the border N with a fern design and conventionalized flowers, as indicated at *n* and *p²*.

I prefer to scallop the upper edge S of the curtain and provide it with a fringe T. The lower edge S' is also preferably provided with a similar fringe.

What I claim is—

The design for a lace curtain, substantially as shown.

HENRY HORSEFIELD.
